UNITED STATES PATENT OFFICE.

ARCHIE NOEL JETTE, OF ANACONDA, MONTANA.

RABBLE FURNACE.

Application filed September 8, 1926. Serial No. 134,273.

This invention relates to metallurgical roasting or drying furnaces of the multiple hearth, rotating shaft type, and more particularly to the heat-insulating mantle 5 rounding the rotating shaft of a furnace of the type mentioned.

It is customary to protect the rotating shaft by an insulating mantle of brick-work or equivalent refractory material, separated 10 from the shaft by an air space, and supported by means of suitable rings attached to the central shaft at the level of each hearth. This means of supporting the mantle is disadvantageous in that the brick-work is not 15 very firmly supported and the motion of the shaft frequently causes the component bricks to drop out, thus exposing the shell of the central shaft.

This invention has for its object to provide 20 an improved method of supporting and retaining the brick-work of the mantle with a view to increasing the working period of the same.

It has been found that superior results are 25 obtained by the use of metal reinforcing rods which engage the bricks at points on their vertical meeting faces, which reinforcing rods rest upon the supporting rings and engage the inner circumferential surfaces of 30 flanges positioned upon the upper and lower surfaces of said rings. As a result of this method of reinforcement the bricks are held firmly in place in the mantle, and the life of the mantle is increased.

35 Any suitably constructed furnace structure capable of handling the material to be treated may be utilized in connection with the present invention.

For a full understanding of the invention 40 reference is made to the accompanying drawings in which:

Fig. 1 is a vertical cross-sectional view of a portion of the central shaft of a rabble furnace and its relation to the plurality of 45 hearths;

Fig. 2 is a horizontal cross-sectional view of the central shaft taken at the line 2—2; and

Fig. 3 is a perspective view of a single 50 brick adapted for use in the construction of the mantle.

Roasting and drying furnaces of the different types are so well known that for the sake of simplicity the furnace proper will 55 be indicated only by the portions of the hearths 9 adjacent the central shaft.

According to this invention the bricks 1 employed for this type of construction have complementary recesses 10 at the midpoint of each end face, semi-circular in cross-section, and of a radius slightly greater than the reinforcing rod 5. The method of constructing the mantle preferably is as follows. One complete vertical course of brick 1 is laid upon the supporting ring 2 at 60 attached to the shell of the central shaft 3, in such manner that the semi-circular recesses at the ends of said bricks register. The mantle preferably is of such inside diameter as to allow a suitable air space 4 between the 65 mantle and the shell 3 of the central shaft. Reinforcing rods 5 are then set into place in the circular recesses between the bricks, and the next complete vertical course is laid, continuing thus until the mantle is completed. 70

The reinforcing rods are held in place by the inner circumferential surfaces of annular flanges 6 positioned upon the upper and lower surfaces of the supporting ring 2. 75

I also propose an improved construction of a lute ring which is applicable to the mantle structure herein disclosed. In a previous United States Patent No. 1,535,160, dated April 28, 1925, a lute ring construction was 80

shown in which the lute ring was placed upon the supporting ring 2 without being rigidly attached thereto, thus permitting expansion or contraction of the one without affecting the other, and by this means preventing breakage caused by unequal expansion. A similar type of construction is to be employed in connection with the present invention with the following change. Figure 85

1 of the Patent No. 1,535,160, shows a portion of the lute ring of such a shape as to lie upon the upper surface of the rib of the supporting ring 2 and positioned between the latter and the bottom course of brick. I now propose to construct the lute ring 90

7 in the form shown in Figure 1 of the accompanying drawings. The depending flange 8 of the lute ring 7, having the shape shown in the drawing, is fitted between the upper flange of the supporting ring 2 and the outer face of the brick 1, and does not interfere with the retaining lugs 6 and the reinforcing rods 5. 100

It is obvious that changes in the forms of the several parts could be effected without departing from the scope of the present invention. Thus, the recesses in the end 110

faces of the bricks could be fashioned to effect contact with a reinforcing rod which might be square, hexagonal or oval in cross-section. Or openings may be provided 5 through the body portion of the bricks for the reception of the retaining rods. Likewise changes in the exact form of the lute ring as shown might be made without departing from my invention which is particularly pointed out in the appended claims.

I claim:

15 1. A rabble furnace of a type having an insulating mantle surrounding a central shaft and carried by supporting rings thereon characterized by the fact that the bricks composing said mantle are maintained in position by vertically disposed reinforcing rods which pass through the mantle and engage said supporting rings.

20 2. A rabble furnace as claimed in claim

1, wherein the meeting ends of adjacent bricks are provided with complementary recesses which form vertical passages for the reception of said reinforcing rods.

3. In a rabble furnace, the combination 25 with a central shaft of supporting rings attached thereto and having annular flanges thereon, an insulating mantle surrounding said central shaft and supported by said supporting rings, said mantle comprising brick-work and vertically disposed reinforcing rods positioned within recesses occurring in 30 said brick-work and retained by said annular flanges.

4. A rabble furnace as claimed in claim 3 35 in which an annular lute ring having a depending circular flange is supported on the outer flange of an annular supporting ring.

In testimony whereof, I affix my signature.

ARCHIE NOEL JETTE.
